(57) **CLAIM**

The ornamental design for a chafing stand, as shown and described.

DESCRIPTION

FIG. 1 is a front perspective view of a chafing stand according to the present invention.

FIG. 2 is a front elevation view of the chafing stand illustrated in FIG. 1.

FIG. 3 is a rear elevation view of the chafing stand illustrated in FIG. 1.

FIG. 4 is a side elevation view of the chafing stand illustrated in FIG. 1.

FIG. 5 is another side elevation view of the chafing stand illustrated in FIG. 1.

FIG. 6 is a top plan view of the chafing stand illustrated in FIG. 1.

FIG. 7 is a bottom plan view of the chafing stand illustrated in FIG. 1.

FIG. 8 is a perspective view of the chafing stand illustrated in FIG. 1 in a separated configuration.

FIG. 9 is another perspective view of the chafing stand illustrated in FIG. 1 in a separated configuration.

FIG. 10 is a front elevation view of a longer panel of the chafing stand illustrated in FIG. 1.

FIG. 11 is a rear elevation view of the longer panel illustrated in FIG. 10 of the chafing stand illustrated in FIG. 1.

FIG. 12 is a side elevation view of the longer panel illustrated in FIG. 10 of the chafing stand illustrated in FIG. 1.

FIG. 13 is another side elevation view of the longer panel illustrated in FIG. 10 of the chafing stand illustrated in FIG. 1.

FIG. 14 is a top plan view of the longer panel illustrated in FIG. 10 of the chafing stand illustrated in FIG. 1.

FIG. 15 is a bottom elevation view of the longer panel illustrated in FIG. 10 of the chafing stand illustrated in FIG. 1.

FIG. 16 is a front elevation view of a shorter panel of the chafing stand illustrated in FIG. 1.

FIG. 17 is a rear elevation view of the shorter panel illustrated in FIG. 16 of the chafing stand illustrated in FIG. 1.

FIG. 18 is a side elevation view of the shorter panel illustrated in FIG. 16 of the chafing stand illustrated in FIG. 1.

FIG. 19 is another side elevation view of the shorter panel illustrated in FIG. 16 of the chafing stand illustrated in FIG. 1.

FIG. 20 is a top plan view of the shorter panel illustrated in FIG. 16 of the chafing stand illustrated in FIG. 1; and,

FIG. 21 is a bottom plan view of the shorter panel illustrated in FIG. 16 of the chafing stand illustrated in FIG. 1.
